UNITED STATES PATENT OFFICE.

GEORGE JARVIS LORD, OF NEW ORLEANS, LOUISIANA, ASSIGNOR OF ONE-HALF TO JOHN EDWARD THORSELL AND ONE-FOURTH TO JOHN R. HUNTER, OF ALEXANDRIA, LOUISIANA, AND ONE-FOURTH TO RUTH WIGGINS, OF NEW YORK, N. Y.

AUTOMATICALLY-MOVING SIGN.

No. 880,815.

Specification of Letters Patent.

Patented Feb. 25, 1908.

Application filed May 20, 1907. Serial No. 374,707.

To all whom it may concern:

Be it known that I, GEORGE JARVIS LORD, a citizen of the United States, residing at New Orleans, in the parish of Orleans, State 5 of Louisiana, have invented certain new and useful Improvements in Automatically-Moving Signs; and I do hereby declare the following to be a full, clear, and exact description of the invention, such as will enable others 10 skilled in the art to which it appertains to make and use the same.

The object of my invention is to provide a moving sign which shall be automatically moved by the motion of the vehicle upon 15 which it is carried, and to this end I provide a movable disk or disks carrying a series of signs or other advertising matter, and cause the same to be actuated by a spring pawl or pawls controlled by a weight or weights, 20 which weights are moved vertically or horizontally by the movement of the vehicle carrying the sign, all as will more fully appear hereinbelow.

Referring to the accompanying drawings 25 forming a part of this specification,—Figure 1 represents an elevation of my improved sign with the back plate removed, and Fig. 2 represents a sectional view on the line X—Y of Fig. 1. Fig. 3 represents an elevation of 30 the slotted guide piece.

Like letters of reference refer to like parts in all of the views.

I represents a dial of any suitable material, and provided around its periphery with a 35 series of signs, or groups of advertising matter, Q represents the back plate, and R the front plate of the casing containing my sign, the plate R being provided with the aperture J through which the various signs or other 40 advertising matter may be successively read.

The dial I is rotatably mounted on the short shaft L, as is also the ratchet wheel F, and disk H fastened to the same, serves to hold the dial I in place. The disk K is provided on 45 the rear side of the dial I, as shown, and by means of screws or other fastenings is secured through said dial I to the disk H. The disks H and K serve to stiffen the structure.

Supported securely at D, and extending 50 across the rear of the dial I, as shown, is the spring E. The free end of this spring passes through the slotted guide A, and carries the adjustable weight C, and near its middle it carries the adjustable spring pawl G, as shown.

B is a bent spring detent to prevent backward movement of the ratchet F. 55

M is a spring pin passing through the shaft L to hold the parts securely in place. Suspended from shaft L, by the rod N is the weight O, and the spring pawl P is attached 60 to said rod and engages the ratchet F, as shown.

The operation of my improved sign is as follows:—The individual signs or groups of advertising matter are so spaced around the 65 periphery of the dial I that one of the same conveniently fills the aperture J, the others being concealed behind the front plate R. When the vehicle carrying said sign is in motion, however, the jolting of the same 70 causes the weight C to move up and down, and to thereby reciprocate the pawl G over the ratchet F, and to turn the same together with the dial I and the signs or advertising matter thereon, causing said signs to continuously change at the opening J, and thereby aiding in attracting the attention of 75 passengers thereto. This motion is also caused by the swinging of the weight O horizontally. In other words the weight C will be caused to 80 move up and down by jolts or like movements in the vehicle, and the weight O to move horizontally by side wise movements in the vehicle if the sign is supported on an end of the same, or by longitudinal movements of 85 the vehicle, if the sign is supported on the side wall of the same. No matter what the movements of the vehicle may be, one or the other of said weights will receive an impulse, since they are supported at substantially right angles to each other, and one or the other will therefore communicate its motion to the sign.

Having described my invention, what I claim and desire to secure by Letters Patent, 90 is:—

1. In an automatic sign, the combination of a suitable apertured casing, a rotatable dial therein, a ratchet, two disks one on each side of said dial, a shaft on which said dial, disks and ratchet rotate, a spring secured at 95 one end and free to swing at its other end, a weight on the free end of said spring, a guide for said spring, a pawl carried by said spring and engaging said ratchet, and a detent pawl for preventing a backward motion of said 100 ratchet, substantially as described.

2. In an automatic sign, the combination of a suitably apertured casing, a rotatable

dial therein, a ratchet, two disks one on each side of said dial and secured to the same, a shaft on which said dial, disks and ratchet rotate, a spring pin securely holding the 5 parts together, a spring secured at one end and free to swing at its other end, a weight adjustably secured to the free end of said spring, a slotted guide compelling said free end of said spring to move in a vertical path, 10 a pawl carried by said spring and engaging said ratchet, and a bent detent pawl for preventing a backward motion of said ratchet, substantially as described.

3. In an automatic sign, the combination 15 of a suitable apertured casing, a rotatable dial therein, a ratchet, two disks one on each side of said dial, a shaft on which said dial,

disks and ratchet rotate, a spring secured at one end and free to swing at its other end, a weight on the free end of said spring, a guide 20 for said spring, a pawl carried by said spring and engaging said ratchet, a rod suspended from said shaft, a weight carried by said rod, a pawl carried by said rod and engaging said ratchet, said rod and said spring being at 25 substantially right angles to each other, and a detent pawl for preventing backward motion of said ratchet, substantially as described.

In testimony whereof, I affix my signature, in the presence of two witnesses.

GEORGE JARVIS LORD.
